UNITED STATES PATENT OFFICE

2,604,072

PNEUMATIC IMPACT DEVICE

Donald E. Beckett and William N. Beckett, Wilmington, Ohio, assignors of one-fourth to Heber W. Harcum and one-fourth to J. Bates Harcum, both of Wilmington, Ohio

Application April 5, 1949, Serial No. 85,622

5 Claims. (Cl. 121—21)

1

This invention relates to a pneumatic hammer of the type adapted to deliver one working stroke or blow in response to each actuation of a control or trigger valve.

An object of the invention is to provide a pneumatic impact hammer which includes a reciprocable hammer piston which is driven forwardly in a power or impact stroke and then retracted rearwardly therefrom by means of fluid pressure which is operative to normally maintain the piston at one or the other ends of its stroke pending the application of a deliberate action on the part of an operator for shifting the piston to the other end of its stroke.

A further object of the invention is to provide a universal type pneumatic impact hammer which may be operatively associated, as a piece of standard equipment, to and with various types of work engaging members, such as, by way of example, nailing guns, punch presses, stapling machines, punching mechanisms, broachers, shears, riveting guns, tamping hammers, chipping machines, and the like.

Still a further object of the invention is to provide a pneumatic impact device which includes a reciprocable hammer piston, the stroke of which is less than the overall length of the piston. Another object of the invention is to provide a pneumatic impact device which is so constructed and arranged that the hammer piston is accelerated throughout its driving stroke up to the moment of impact with a work engaging member associated therewith.

A further object of the invention is to provide a pneumatic impact device wherein the hammer piston is free of bounce-back or rebound after completion of a driving stroke, said piston being maintained at the end of its power stroke under full line pressure until released therefrom by a deliberate act on the part of the operator.

Another object of the invention is to provide a pneumatic impact device wherein the hammer is maintained in a fully retracted position by air pressure confined within a comparatively small air chamber as compared with the cross-sectional area of the cylinder behind the hammer, thereby eliminating, for all practical purposes, back pressure which would retard the forward driving stroke of the hammer.

Another object of the invention is to provide a simple, yet highly effective means for controlling an operating valve means for controlling the operating characteristics of the hammer piston of a pneumatic impact device, wherein the operating characteristics of the valve are pneumatically controlled, said valve being so constructed and arranged as to normally direct full line pressure to the hammer piston for driving and maintaining it at one or the other ends of its stroke.

Still another object of the invention is to pro-

2

vide a pneumatic impact device which comprises an integral unit capable of being operatively associated with any desired type of cradle, housing or handle thereby greatly enhancing its overall utility.

Another object of the invention is to provide a pneumatic impact device having the hereinabove described characteristics which is considerably more efficient, less expensive and simpler in construction than any other pneumatic impact device of which we are aware. By way of example, when operated on 100 pounds air pressure thru a 10 inch stroke in a cylinder having an inside diameter of 3½ inches, our hammer will develop and deliver a 50,000 pound blow to a suitable work engaging member associated therewith.

These and other objects are attained by the means described herein and as disclosed in the accompanying drawings, in which:

Fig. 1 is a sectional view taken thru a pneumatic impact tool embodying the teachings of the present invention, showing the relationship of various parts thereof at the start of a power stroke.

Fig. 2 is a view similar to Fig. 1 but showing the relationship of the various elements at the start of a return stroke of the hammer piston.

With reference now to Figs. 1 and 2, the numeral 10 indicates a cylinder within which a hammer piston 12 is reciprocably mounted. The diameter of the body portion of piston 12 is of a dimension less than the inside dimension of cylinder 10 for providing an air chamber 14 therebetween. The difference in diameters may, by way of example, approximate from ¼ to ½ inch.

If desired, the rear portion of piston 12 may be enlarged as at 16, said enlarged portion dimensioned for a loose sliding fit within the cylinder. Suitable sealing means, such as, by way of example, an O-ring 18, or the like, may be secured to and carried by the rear portion of piston 12, said sealing means being receivable within annular groove 20 whereby to engage the inner face of cylinder 10 for providing a sliding air and fluid tight fit.

At this point, it should be clearly understood that the overall stroke of piston 12 is of a dimension less than its overall length.

In the preferred embodiment of the invention the forward end 22 of the hammer piston is adapted to engage rear face 24 of an anvil 26 of a work engaging member suitably secured to the forward end of the cylinder. In Fig. 1, the work engaging member includes an outer casing 28 which is secured in abutting relationship to annular sleeve 30 carried by the forward end of cylinder 10 by means of a strap-like member 32.

Cylinder 10 and casing 28 of the work engaging member may be received within a combina-

tion hand grip and supporting unit denoted generally by the numeral 40, it being understood that those portions of casing 28 remote from cylinder 10 terminate in a suitable tool, such as, by way of example, a nailing machine, a riveting gun, a punching mechanism, a broaching device, a shearing mechanism, a stapling machine, or other suitable member.

Sealing means 42 are secured relative to the forward end of cylinder 10 for engaging the forward portion of the hammer piston when in a fully retracted position, thereby defining the front wall or end of an air chamber 14, the rear wall or end of which is defined by sealing means 18. If desired, an annular sleeve 30 is secured to the forward end of cylinder 10 having an undercut portion 44, carrying sealing means 42. The internal diameter of sleeve 30 is dimensioned for a sliding fit with the body portion of piston 12, said sleeve providing a bearing or alignment support for the piston incident to its reciprocation within the cylinder.

With reference now to Fig. 2, it will be observed that the area of air chamber 14 is quite small during those periods of time when piston 12 is disposed at the forward end of its power or driving stroke, said area varying from a maximum when the piston is fully retracted, as in Fig. 1, to a minimum when the piston is fully extended as in Fig. 2.

The operating characteristics of the hammer piston are controlled by a valve assembly denoted generally by the numeral 50 which may be received and housed within that end of cylinder 10 remote from the work engaging member. This assembly comprises a valve block 52 having an axial bore 54 (see Fig. 2) extending longitudinally therethru. The valve block 52 may be dimensioned for a tight sliding fit within cylinder 10, being sealed in place by means of sealing means 130 and 132. A plurality of annular ports 56, 58, 60, 62 and 64 are provided in open communication with axial bore 54. A piston rod 66 is reciprocably mounted in said bore, said piston rod including pistons 68, 70, 72 and 74, which are constructed and arranged to cooperate with various of said annular ports for controlling the flow of air to the hammer piston.

With reference now to Fig. 1, piston rod 66 is disposed in the forward of its two normal positions, wherein pistons 70 and 72 are located on opposed sides of adjacent ports 58 and 60 thereby interconnecting said ports. Port 60 is disposed in open communication with passageway 80 which extends thru valve block 52, the wall of cylinder 10, thence into element 40. Passageway 80 is in open communication with passageway 82, the lower free end of which is normally connected to a source of air under pressure.

From the foregoing, it will be observed that full line pressure will always be maintained within annular port 60, and when the piston rod has been shifted forwardly, as in Fig. 1, the full line pressure will be communicated to port 58, thence to intake port 90 which is in open communication with the rear face of piston 12.

A second inlet port 92 is provided thru cylinder 10 adjacent the forward end of the piston when in a fully retracted position and in open communication with air chamber 14. With reference to Fig. 2, it will be observed that inlet port 92 is so located as to be in open communication with the minimum area of air chamber 14 as defined by piston 12 when at the forward end of a power stroke. Inlet port 92 may

be interconnected by means of a conduit 94 to annular port 62 of the valve. Annular ports 56 and 64 are exhaust ports suitably vented through valve block 52 to the atmosphere. With reference again to Fig. 1, it will be noted that port 92 is in open communication with exhaust port 64 whereby the air within air chamber 14 will be freely exhausted incident to forward motion of piston 12.

We have found that excellent results are obtained when pneumatic means are used for effecting reciprocation of piston rod 66 for controlling the actuating characteristics of hammer piston 12. An auxiliary air chamber 100 may be provided rearwardly of valve block 52 whereby to house the rear end of piston rod 66. Air from passageway 80 may be introduced into auxiliary chamber 100 thru conduits 102 and 104, the flow of air being controlled by means of valve head 106 secured to and carried by valve stem 108 reciprocably mounted in block 113 suitably threaded or sealed in element 40 as at 111. The valve stem is normally urged to the right to a seated position by means of spring 110. Valve head 106 is adapted to seat against a suitable valve seat 112 (see Fig. 2), for precluding a flow of air from passageway 80 to conduit 104. The body of valve stem 108 is provided with an undercut portion 114 thru which the air within the auxiliary chamber 100 and conduits 102 and 104 may be exhausted when the valve stem is seated. When the pressure within the auxiliary chamber 100 has thus been released piston rod 66 will be shifted rearwardly from the position illustrated in Fig. 1 to the position illustrated in Fig. 2 by means of the pressure within cylinder 10 which pressure will act upon forward end 118 of piston 68, thereby connecting the line pressure to annular port 62 and inlet port 92 while interconnecting passageway 90 to exhaust port 56.

Actuation of valve stem 108 may be effected by means of a lever 120 pivotally secured as at 122 to handle portion 124 of element 40. It will be understood that lever 120 will be moved forwardly for unseating valve stem 108 incident to a squeezing action applied to hand grip 124 by the operator.

The extent of axial travel of piston rod 66 may be governed by collar 134 threadably secured to the rear end of the piston rod, said collar including portions adapted to abut against the rear face of valve block 52 for limiting the forward travel of the piston rod.

From the foregoing, it will be observed that piston 12 will be driven forwardly or rearwardly within cylinder 10 and maintained at the end of its forward or return stroke by full line pressure. It has been found that when lever 120 is actuated for unseating valve stem 108 piston rod 66 will be instantly snapped forwardly thereby introducing a steady blast of compressed air under full line pressure thru passageway 90 to the rear face of the hammer piston 12 for driving the piston forwardly with ever increasing acceleration up to the time of its impact with anvil 26 of a work engaging member. The effectiveness of our device will immediately become apparent when it is noted that we are able to develop a 50,000 pound impact thru a 10 inch stroke in a 3½ inch cylinder at 100 pounds air pressure. A device having a cylinder with a 1½ inch inside diameter and an effective piston stroke of 4 inches operating on 75 pounds pressure will operate a commercial nailing gun with

such effectiveness as to drive and countersink $1\frac{1}{4}$ inch rectangular nails into hard wood.

It will be observed that air is utilized to control both the actuating valve and the hammer piston whereby the need of springs has been completely eliminated. The structural characteristics of the device are such that there is substantially no back pressure opposing the forward driving stroke of piston 12. This is true because of the small area of air chamber 14, the total or overall area of which is continuously reduced as piston 12 moves forwardly. Although the cross-sectional area of air chamber 14 is small, it is nevertheless quite sufficient to effect an almost instantaneous return of piston 12 from the fully extended position of Fig. 2 to the fully retracted position of Fig. 1. Experiments and actual usage have conclusively proven that the operating cycle is practically instantaneous with actuation of lever 120.

If desired, a spring, not illustrated, may be interposed between collar 134 and the end of valve block 52 for precluding accidental or unintentional shifting of piston rod 66 to an impact delivering position of Fig. 1 during those periods of time when the line pressure has been disconnected or during those periods of time when the pressure on opposite ends of the piston rod is substantially equal so that it could shift of its own weight incident to movement of the device, such as, in the normal handling and usage thereof.

What is claimed is:

1. A manually portable pneumatic tool of the character described comprising a cylinder, a hammer piston reciprocable therein, a work engaging member at one end of said cylinder disposed to be struck by said piston, a valve assembly secured to, carried by and housed within the other end of said cylinder, an air chamber provided between said piston and cylinder, sealing means secured to and carried by the rear portion of said piston engaging the inner wall of said cylinder, sealing means secured relative to said cylinder engaging the forward portion of said piston when in a fully retracted position, an air port in open communication with the air chamber surrounding said piston, said valve assembly including a valve block in that end of the cylinder remote from said work engaging member, said block having an axial bore having a plurality of annular ports in open communication therewith, a piston rod reciprocably mounted in said bore, pistons on said rod for cooperation with various of said ports, means for continuously directing compressed air to one of said annular ports, means interconnecting a second annular port in open communication with said air port, means interconnecting a third annular port in open communication with said cylinder rearwardly of the piston when in a fully retracted position, said piston rod reciprocable for connecting one or the other of said second and third annular ports in open communication with said first annular port and for simultaneously exhausting the other port for driving and maintaining said hammer piston at one or the other ends of its stroke, and manually controlled means for selectively introducing compressed air onto opposite ends of said piston rod for reciprocating same.

2. A pneumatic tool of the character described comprising a cylinder, a hammer piston reciprocable therein, a work engaging member at one end of said cylinder disposed to be struck by said piston, a valve assembly secured to, carried

by and housed within the other end of said cylinder, an air chamber provided between said piston and cylinder, sealing means secured to and carried by the rear portion of said piston engaging the inner wall of said cylinder, sealing means secured relative to said cylinder engaging the forward portion of said piston when in a fully retracted position, an air port in open communication with the air chamber surrounding said piston, said valve assembly including a valve block received in that end of the cylinder remote from said work engaging member, said block having an axial bore having a plurality of annular ports in open communication therewith, a piston rod reciprocably mounted in said bore, pistons on said rod for cooperation with various of said ports, means for continuously directing compressed air to one of said annular ports, means interconnecting a second annular port in open communication with said air port, means interconnecting a third annular port in open communication with said cylinder rearwardly of the piston when in a fully retracted position, said piston rod reciprocable for connecting one or the other of said second and third annular ports in open communication with said first annular port and for exhausting the other port for driving and maintaining said hammer piston at one or the other ends of its stroke, and means operable for reciprocating said piston rod for controlling the stroke of said hammer piston, one end of the axial bore of said valve in open communication with the interior of said cylinder, an auxiliary air chamber in open communication with the opposite end of said axial bore, manually controlled means for selectively directing compressed air into said auxiliary air chamber for driving said valve piston rod forwardly for connecting said first and third annular ports for directing compressed air onto the rear face of said piston to drive said piston forwardly on its power stroke, said piston rod shiftable rearwardly upon release of pressure in said auxiliary chamber for connecting said first and second annular ports for directing compressed air into the air chamber surrounding said hammer piston to return and maintain said piston in a fully retracted position.

3. A pneumatic impact hammer comprising a cylinder, a hammer piston reciprocable therein through a power stroke and a return stroke, an air chamber surrounding said piston, sealing means secured relative to the rear portion of the piston slidably engaging said cylinder, other sealing means secured relative to the cylinder slidably engaging said piston, said sealing means defining the front and rear ends of the air chamber surrounding said piston, a valve assembly housed within the cylinder rearwardly of the rearmost end of the piston when at the end of a return stroke, said assembly including a reciprocable valve member in axial alignment with the cylinder and with its forward end in open communication with the interior of the cylinder, manually controlled means for selectively supplying motive fluid under full line pressure to the rear end of said valve member for shifting it forwardly to a position where motive fluid will be directed into said cylinder for driving the piston forwardly and maintaining it in a fully advanced position, said valve member shiftable rearwardly by the pressure within said cylinder between the piston and forward end of said valve member incident to release of motive fluid from the rear end of said valve member to a position

where motive fluid will be directed into the air chamber surrounding the piston for driving said piston rearwardly to a fully retracted position and of maintaining it in retracted position until the actuation of said manually controlled means.

4. A manually operable pneumatic tool of the character described comprising a cylinder, a hammer piston reciprocable therein, a work engaging member at one end of said cylinder disposed to be struck by said piston, a valve assembly secured to, carried by and housed within the other end of said cylinder, an air chamber provided between said piston and cylinder, sealing means secured to and carried by the rear portion of said piston engaging the inner wall of said cylinder, sealing means secured relative to said cylinder engaging the forward portion of said piston when in a fully retracted position, an air port in open communication with the air chamber surrounding said piston, said valve assembly including a valve block disposed within that end of the cylinder remote from said work engaging member, said block having therethrough an axial bore having a plurality of annular ports in open communication therewith, a piston rod reciprocably mounted in said bore, pistons on said rod for cooperation with various of said ports, means for continuously directing compressed air to one of said annular ports, means interconnecting a second annular port in open communication with said air port, means interconnecting a third annular port in open communication with said cylinder rearwardly of the piston when in a fully retracted position, said piston rod reciprocable for connecting one or the other of said second and third annular ports in open communication with said first annular port and for exhausting the other port for driving and maintaining said hammer piston at one or the other ends of its stroke, one end of said piston rod normally in open communication with the interior of said cylinder rearwardly of the hammer piston, a second valve block disposed within the chamber and abutting the first valve block, said second valve block including an auxiliary air chamber in axial alignment with the bore of said first valve block and housing the other end of said piston rod, manually controlled means for delivering a blast of air into said auxiliary chamber for driving and maintaining said piston rod in a fully advanced position for simultaneously exhausting the air in said air port surrounding the hammer piston and instantaneously introducing air under full line pressure into the cylinder rearwardly of said hammer piston for driving it forwardly under full line pressure to the end of its stroke, said manually controlled means adapted to exhaust air from said auxiliary chamber for driving said piston rod to a fully retracted position by the pressure existing in said cylinder behind the hammer piston for simultaneously exhausting the air in said cylinder and instantaneously introducing air under full pressure into said air port surrounding said hammer piston for returning it to a fully retracted position.

5. A manually portable, pneumatic tool of the character described, comprising a cylinder, a hammer piston reciprocable therein, a valve assembly secured to, carried by and housed within one end of said cylinder, sealing means secured to and carried by the rear portion of said piston engaging the inner walls of said cylinder forwardly of said valve assembly, sealing means se-

cured relative to the cylinder remote from said valve assembly for engaging the forward portion of said piston, an air chamber provided between said piston and cylinder and sealing means, said valve assembly including a valve block secured to and received within said cylinder, said valve block having therethrough an axial bore having a plurality of laterally spaced annular ports in open communication therewith, a piston rod reciprocably mounted in said bore, with its forward end in open communication with a second chamber defined by the interior of the cylinder rearwardly of the hammer piston, pistons on said rod for co-operation with various of said annular ports, a third chamber provided in axial alignment and in open communication with the rear end of said bore, the rear end of said piston rod in open communication with the interior of said third chamber, means interconnecting one annular port in open communication with the interior of said first chamber, means interconnecting a second annular port in open communication with said second chamber, said piston rod reciprocable between fully advanced and fully retracted positions for connecting one or the other of said first and second annular ports in open communication with a third annular port while exhausting the other port, means for supplying motive fluid under full line pressure continuously to the third of said annular ports, means for supplying motive fluid under full line pressure to said third chamber, manually operable valve means for controlling the flow of motive fluid to said third chamber or for connecting said third chamber to exhaust, said piston rod shiftable forwardly incident to and solely by the introduction of motive fluid into said third chamber for thereby connecting said second and third annular ports thereby introducing motive fluid under full line pressure directly into the second chamber for driving and maintaining the hammer piston forwardly of said cylinder to the forward end of its stroke, said piston rod and hammer piston remaining at the forward ends of their respective strokes incident to the application of motive fluid under full line pressure within the second and third chambers, said piston rod being automatically shiftable by the pressure within the second chamber from its fully advanced position to a fully retracted position incident to actuation of said manually operable valve for connecting the third chamber to exhaust, said fully retracted piston rod interconnecting the first and third annular ports for supplying motive fluid under full line pressure to the first chamber for driving and maintaining said hammer piston in a fully retracted position.
